SHAVING BLADE DISPENSER

Paul A. Braginetz, Staunton, Va., assignor to Philip Morris Incorporated, New York, N.Y., a corporation of Virginia

Filed Aug. 31, 1965, Ser. No. 86,779

Term of patent 14 years

(Cl. D52—2)

FIG.1

FIG. 2

FIG. 3

FIG. 1 is a top plan view of the shaving blade dispenser showing my new design;

FIG. 2 is a cross-sectional view taken substantially on line 2—2 of FIG. 1, showing the casing of the dispenser depicted in FIG. 1 and with the interior mechanism broken away; and

FIG. 3 is a rear plan view thereof.

The sides of the casing shown in FIGS. 1 and 3 have substantially plain surfaces.

The dominant features of the design reside in the full line portions of the drawing. The broken line showing of the razor blade in FIG. 1 is for illustrative purposes only. The characteristic features of the design reside in the appearances of the top, bottom and sidewall panels of the casing when the latter is viewed in plan from above and below and in side elevation; including, in combination, the convexity of the top panel and the outward bowing in opposite directions of the opposite sides thereof, the generally rectangular depressed central area of the latter and the shape of the oval access hole centrally located in this depressed area, the observable surfaces of this depressed area surrounding this hole which include oppositely sloped and downwardly inclined ramps at opposite ends of the oval access hole and the transversely curved and steeply sloped sides of this depressed area defining the sides of these ramps and immediately flanking the sides of this hole; the rectangular shape and convexity of the bottom panel; the outward bowing in opposite directions of the sidewalls and the oblique sloping in op-

posite directions of the upper half sections of the sidewall end portions and curvilinear shape of the projecting lower half sections of the latter which foreshortens the top panel at both ends, and also the outwardly curved bottom edges of the sidewalls flanking the straight sides of the bottom panel; the opposed fingers and intervening cross-bridge exposed to view in the oval access hole; and the tapered sidewall end tips and transversely-spaced tabs intervening the latter which are exposed to view from above at opposite ends of the foreshortened top panel, all as shown.

I claim:

The ornamental design for a shaving blade dispenser, substantially as shown and described.
